RODENT POISON DISPENSER

Paul M. Dozier, 655 E. LaLoma Ave.
Camarillo, Calif. 93010

Filed Oct. 22, 1968, Ser. No. 14,105

Term of patent 14 years

Int. Cl. D9—04

U.S. Cl. D52—2

FIGURE 1 is a perspective view of a rodent poison dispenser showing my new design;

FIGURE 2 is a rear elevational view thereof;

FIGURE 3 is a front elevational view thereof;

FIGURE 4 is a side elevational view thereof, showing the side opposite to the side shown in FIGURE 1;

FIGURE 5 is a top plan view thereof, taken along the arrow 5 of FIGURE 2; and,

FIGURE 6 is a bottom plan view thereof, taken along the arrow 6 of FIGURE 2.

The dominant features of the design reside in the portions shown in full lines and the immaterial features of the design reside in the portions shown in broken lines.

I claim:

The ornamental design for a rodent poison dispenser, substantially as shown and described.
